CLAIM

The ornamental design for an electronic device charger, as shown and described.

DESCRIPTION

FIG. 1 is a perspective view of an electronic device charger, showing my new design;

FIG. 2 is a right side elevation view of FIG. 1;

FIG. 3 is a left side elevation view of FIG. 1;

FIG. 4 is a front elevation view of FIG. 1;

FIG. 5 is a top plan view of FIG. 1;

FIG. 6 is a bottom plan view of FIG. 1;

FIG. 7 is a rear elevation view of FIG. 1; and,

FIG. 8 is an exploded view of FIG. 1.

(Continued)

The broken lines depict portions of the electronic device
charger that form no part of the claimed design.

1 Claim, 4 Drawing Sheets
